(57) **CLAIM**

The ornamental design for a nut cracker as shown and described.

DESCRIPTION

FIG. 1 is a top, right-side perspective view of a nut cracker showing my new design;

FIG. 2 is a top, left-side perspective view of the nut cracker shown in FIG. 1;

FIG. 3 is an enlarged, bottom, partial right-side perspective view of the nut cracker shown in FIG. 1;

FIG. 4 is a front elevation view of the nut cracker shown in FIG. 1;

FIG. 5 is a rear elevation view of the nut cracker shown in FIG. 1;

FIG. 6 is a top plan view of the nut cracker shown in FIG. 1; and,

FIG. 7 is a bottom plan view of the nut cracker shown in FIG. 1.

The dot-dot-dash broken lines shown in the figures depict a partial portion of the nut cracker that form no part of the claimed design.

1 Claim, 5 Drawing Sheets
